UNITED STATES PATENT OFFICE.

EMERSON A. BOLEN, OF MORRIS, ILLINOIS, ASSIGNOR TO NORTH WESTERN NOVELTY COMPANY, OF MORRIS, ILLINOIS, A CORPORATION OF ILLINOIS.

COIN-CONTROLLED VENDING-MACHINE.

1,140,438.

Specification of Letters Patent. Patented May 25, 1915.

Application filed October 26, 1912. Serial No. 727,820.

To all whom it may concern:

Be it known that I, EMERSON A. BOLEN, a citizen of the United States, residing at Morris, in the county of Grundy and State 5 of Illinois, have invented certain new and useful Improvements in Coin-Controlled Vending-Machines, of which the following is a specification.

My invention relates to improvements in 10 coin controlled vending machines, and in some of its features has particular reference to machines for vending packaged articles such as boxes of matches and the like.

Among the objects of my invention is to 15 provide a machine of the character described which is attractive in appearance, small in size, simple and rugged in construction, not liable to get out of order, and positive and efficient in its operation.

20 The present application relates particularly to coin controlled apparatus and combinations of the same with a vending machine, and in a divisional application filed by me December 8th, 1913, serially numbered 806,989 and entitled Dispensing apparatus, I have described, illustrated and claimed the vending machine *per se*.

25 In the drawings wherein I have shown an embodiment of my invention in a machine for vending boxes of matches Figure 1 is a vertical section from front to back of the machine taken on line 1—1 of Fig. 2; Fig. 2 is a vertical section transversely through the machine taken on line 2—2 of Fig. 1; Fig. 3 is a horizontal section on line 3—3 of Fig. 2, showing certain of the parts in inverted 30 plan view; Fig. 4 is a perspective detail of the fragment of the mechanism as seen from below; and Fig. 5 is a perspective detail, 35 with parts broken away, showing the delivery mechanism as seen from above.

40 My present invention, in some of its features, may best be embodied in a structure providing two vertical storage receptacles or compartments for the packages, from 45 which said storage receptacles deliveries may alternately be made. I have accordingly shown my invention embodied in such form of structure, although it will be clear that a single compartment construction might be 50 employed with a retention of some of the advantages.

In the specific construction 10 indicates the base casting which conveniently carries

a cigar cutter 11 and a match box holder 55 12 to receive a sample box of matches, said casting providing in its rear portion a depression 13 forming a coin receptacle. In front of this coin receptacle a vertical face casting 14 is secured upon lugs 15 of the 60 base, said casting 14 carrying a top member 18 and preferably having on its inner surface a vertical rib 16 centrally disposed near the top of the casting. Edge ribs 17 are also provided on the casting to coöperate 65 with the side walls of the back unit.

All of the operating mechanism of the device is arranged in a detachable back unit 20, which provides the back wall 21 and side walls 22—22' of sheet metal to interfit with 70 the base and front-wall castings, said back wall being reinforced by plate 23 carrying in its lower end a lug 24 to interlock in a suitable notch 25 in the base casting. When the back unit is in position as shown in Figs. 75 1 and 3, the side walls 22, 22' fit within the ribs 17 of the front plate, a slot 27 in the upper end of the back wall receives an apertured lug 28 projecting from the top casting 18 so that a padlock may be readily applied 80 to lock the coacting parts in engagement thereby to complete the closure of the device 85 and prevent it being tampered with.

The upper portion of the space inclosed 90 within the structure is vertically divided into two storage compartments by a central partition 30 attached to the back wall 21 and in said partition I preferably form the coin chute 31 in the form of a slot in which engages the rib 16 and which has a coin-recep- 95 tion opening communicating directly with a centrally arranged coin slot 32 in the front casting of the casing. A vertical strip 33 secured in the slot acts as the front wall of the chute to direct the coin in its downward traverse.

The arrangement above described is ad- 100 vantageous in affording a symmetrical di- vision of the casing vertically into the two storage compartments 35—35' and locating the coin chute centrally between said com- 105 partments so that, as hereafter described, the deposited coin may be caused to effect the disabling of the lock mechanism which will permit the delivery of a package first from one compartment and then from the other alternatively.

The side walls 22 and 22' of the casing are

cut away substantially in line with the bottom of the partition 30, so as to form a transversely free slide-way and across the space beneath the slide-way I arrange a 5 bridge plate 40 having a flat top surface and downturned side walls 41 which are secured to the side walls of the back unit. Said bridge plate has its front portion cut away as at 42 and has in its horizontal portion a guide slot 43, separated from the opening 42 by the cam bar 44 the construction and operation of which will be hereinafter described.

Upon the bridge plate I mount the transversely movable delivery slide member 50 which, in the specific construction shown, provides a central elevated platform or ejector part 51 having side walls 52—52' flanked by two corresponding package recesses 53—53' formed by the horizontal bottom walls 54—54' and the upturned side walls 55 and 55' which also constitute the finger pieces for the operation of the slide. The slide member is longer than the casing 20 25 is wide and extends through the casing from side to side. Its arrangement is such that when it stands at one extreme of its limit of movement, one of its delivery recesses, say 55' registers with the storage 30 compartment 35' thereabove; its central platform 51 substantially closes the bottom of the other storage compartment 35 and its remaining delivery recess 55 projects beyond the side wall 22 of the casing to present any package that may be contained 35 40 therein in position for easy removal from the slide. It will therefore be apparent that in the absence of any coin-controlled locking mechanism the slide could be slipped back and forth at pleasure, each excursion of the slide from one limit of movement to the other delivering a package from within the storage receptacle to a position exteriorly accessible from one side of the 45 casing and such delivery taking place alternately with respect to the two storage receptacles.

The structure providing the platform and delivery recesses is preferably made integral, and in the form shown in Fig. 2, the walls 54, 54', have, on their under side, ribs 56, 56' to engage in the guide slot 43, but the space under the platform is left unobstructed for the reception of the coin-controlled releasing mechanism to be described. Guide pieces 57 and 57' secured on the ribs 56, 56' serve to limit the throw of the slide member by contacting with the side walls 41 of bridge member 40, and they also serve to 55 60 retain the slide against vertical displacement with respect to the bridge member.

It will be observed with respect to Fig. 2 that the width of the platform 51 is greater than the limit of movement of the slide structure, so that some portion of said plat-

form is always located directly below the coin chute. Coin-receiving slots 60 and 60' are formed in the platform 51 at points appropriate to be brought in register with the coin chute when the slide structure is 70 respectively at its opposite limits of movement, the solid surface of the platform closing the chute at all times save when one of these two slots 60 or 60' registers therewith.

The coin-controlled locking mechanism 75 for the slide structure may be made in various forms, that which I prefer being located under the platform.

61 indicates a casting secured to the under side of the platform 51 and having side walls 62—62' underlying the adjacent edges of coin slots 60—60', and spaced apart from walls 52, 52', as to form in the base two coin-receiving pockets respectively defined as to their front ends by lugs 63—63' extending from the side walls of the casting 61. The rear walls of the two coin pockets are formed by the edge surfaces of two pivoted dogs 65 and 65', mounted upon a pivot pin 66 and both acted upon by spring 67 80 which tends to move the top of each dog in the rearward direction. Each dog has its nose 68 or 68' which coacts with the coin so eccentrically shaped that movement of the dog in the direction of spring tension 85 90 tends to reduce the distance between the nose of the dog and the lug 63 or 63' forming the front wall of the coin pocket to a distance less than the diameter of the coin, while opposite movement of the dog may retract 100 its nose from said lug to open the space between them to more than the diameter of the coin. Each dog has a trigger 69 extending down into the guide slot 43 so that the spring pressure on the dog maintains it in 105 sliding engagement with the edge of the cam bar 44. The cam bar, as best shown in Figs. 3 and 4, provides centrally a crest 70; opposite locking inclines 71 and 71' flanking the crest and terminating at the respective shoulders 72—72', the extremities of which substantially aline with the crest; straight surfaces 73—73' continuing from the extremities of said shoulders; and terminal releasing inclines 74—74' extending 110 beyond the line of said crest and shoulders. The operation of these parts is as follows: Assuming the slide to be at one end of its limit of movement, as shown in Fig. 3, the trigger 69 is spring-held against the crest 115 of the cam bar. If, now, effort be made to move the slide to opposite extreme of movement, without the insertion of a coin, the slide may move only a short distance, for as it moves transversely the tension of 120 spring 67 causes the trigger 69' to follow the edge of the cam bar and slip down the latching incline 71' until it strikes against the shoulder 72' to stop the movement of 125 the slide. If now the slide be moved back 130

to its starting position, so that the trigger 69' of the dog rides up the crest again, and a coin be inserted in the coin chute, said coin will travel down the chute and drop 5 into the coin-receiving pocket where it lies wholly below the level of the platform between the walls 52' and 62', the coin being retained in the pocket in the position as shown in Fig. 4 where it is interposed between the lug 63' and the nose 68' of the dog 65'. Now when the slide is moved transversely the presence of the coin interposed between the nose of the dog and the opposing abutment 63' prevents the trigger 10 69' from following the edge of the cam bar 44, so that said trigger passes by the shoulder 72' without striking it and the full movement of the slide may be effected. As the slide approaches its further limit of 15 movement the trigger 69' rides along the releasing incline 74', so that the dog is forced over against the restraining action of its spring, removing its nose from restraining relation with respect to the coin and 20 freeing the coin to drop through the space between the nose of the dog and the opposing lug 63' into the coin receptacle 13 in the base of the structure.

It will be apparent now that in whichever 25 extreme of position the slide may stand, the insertion of a coin frees it for movement to its other extreme of position and automatically conditions the mechanism to receive another coin to permit an opposing movement 30 of the slide back to its original position, so insuring that delivery will be made first on one side of the machine, from one storage receptacle, and then on the other side of the machine from the other storage receptacle, the same coin chute centrally located, serving to deliver coins alternately to the two controlling means. The action is 35 positive, the parts are simple, and the slide action is very free. As a further refinement, the relation of the parts is such that in case 40 a second coin is sent down the chute 31, while the first is engaged between the lug 63 and nose 68 (Fig. 1, dotted lines), said second coin strikes the first and passes 45 thence under the lower edge of the strip 33 and out through perforation 80 to be returned to the owner. The strip 33, however, extends low enough to prevent discharge of a coin which rests upon the platform 50 51 so that a coin so resting will fall into dotted-line position (Fig. 1) as soon as slot 60 is brought thereunder.

As best shown in Fig. 2 I prefer that the 55 parts be so proportioned with respect to the packages to be sold that the delivering movement of the slide shall not completely move the package contained in the exposed delivery recess from under the edge of the package next above it in the storage receptacle, so that if one should fail to remove

a package which is positioned for delivery it will not block the operation of the machine.

While I have herein described in some detail a particular embodiment of my invention, which I have found to be practical and advantageous, and some of the details whereof I may claim for their specific advantage, it will be apparent to those skilled in the art that numerous changes in the structure and the arrangement might be made without departing from the spirit of my invention and within the scope of the appended claims.

What I claim is:

1. In a machine of the character described, the combination of a coin controlled slide, having a coin pocket therein; a guide, for said slide, having a fixed cam bar; and a coin disabled dog, engaging said cam bar, locking the slide in the absence of a coin and on the continuous movement of the slide moved by the cam to coin release position.

2. In a machine of the character described, the combination of a coin controlled slide, having a coin pocket therein; a guide, for said slide, having a fixed cam bar; a coin disabled dog, normally in contact with said cam bar; a stop, on said cam bar, engaged by the dog in the absence of a coin; and means, on said cam bar beyond said stop, to move the dog into coin release position.

3. In a machine of the character described, the combination of a coin controlled slide, having a coin pocket therein; a guide, for said slide, having a fixed cam bar; a coin disabled dog, one part of which is normally in contact with said cam bar, another part of which extends into the coin pocket; a projection, on said cam bar, for moving said dog into position to be engaged by a coin when the slide is in coin-receiving position; a second projection, on said cam bar, engaged by said dog at the end of its movement to release the coin; and a stop, on said cam bar intermediate the two projections and engaged by the dog in the absence of a coin.

4. The combination of a coin controlled slide; a support therefor; coin disabled locking means, carried by the slide, said support having a slot therein to receive a projecting part of said locking means; said support at the edge of the slot being cam-shaped, to coact with said projecting part.

5. The combination of a coin controlled slide; a support therefor; coin disabled locking means, carried by the slide, said support having an opening therein to receive the coin when released and a slot therein to receive a projecting part of the said locking means; said support at the edge of the slot being cam-shaped to coact with said projecting part.

6. The combination of a coin controlled

slide; a base part; a support, for the slide, coacting with the said base part to form a coin receiving chamber; coin disabled locking means, carried by the slide, said support having an opening therein to permit the passage of a coin therethrough when released and a slot to receive a projecting part of the said locking means; said support at the edge of the slot being cam shaped to coact with 10 said projecting part.

7. The combination of a coin controlled slide; a support therefor; coin disabled locking means, carried by the slide, said support having a slot therein to receive a projecting part of said locking means; said support at the edge of the slot being cam shaped to coact with said projecting part; and a guide, carried by said slide and extending through the said slot to overlie the under 20 edges thereof.

8. In a machine of the character described, the combination of a coin controlled slide, having two coin pockets therein, adapted to alternately register with a single 25 coin chute when the slide is in one or the other of its two extreme positions; a guide, for said slide, having a fixed cam bar; coin disabled dogs, in said coin pockets, normally spring pressed in contact with said cam bar, 30 locking the slide in the absence of a coin and moved by the cam on continuous movement of the slide to coin release position.

9. The combination of a coin controlled slide, longitudinally movable into two extreme positions; a support therefor; a lock carried by said slide, coin disabled to permit slide movement in one direction; a second independent lock, carried by the slide, coin disabled to permit movement of the 40 slide in the opposite direction; a vertically disposed coin pocket associated with each of said locks and carried by the slide; and a single coin chute, registering with one of said pockets when the slide is in one extreme 45 position and with the other when the slide is in the opposite extreme position.

10. The combination of a coin controlled slide, movable into two extreme positions; a flat support therefor; said slide having a 50 raised central portion; a lock, positioned in said raised portion, coin disabled to permit slide movement in one direction; and a second independent lock, carried by said raised portion, coin disabled to permit movement 55 of the slide in the opposite direction.

11. The combination of a coin controlled slide, having a central raised portion, and movable into two extreme positions; a flat support therefor; a lock, positioned in said 60 raised portion, coin disabled to permit slide movement in one direction; a second independent lock, positioned in the said raised portion, coin disabled to permit movement 65 of the slide in the opposite direction; a coin pocket, associated with each of said coin

locks and positioned in the raised portion of the slide.

12. The combination of a coin controlled slide, having a central raised portion thereon, and movable into two extreme positions; 70 a flat support therefor; a lock, positioned in said raised portion, coin disabled to permit slide movement in one direction; a second independent lock, positioned in said raised portion, coin disabled to permit movement 75 of the slide in the opposite direction; a coin pocket, associated with each of said locks and positioned in the raised portion of the slide; and a single coin chute, registering with one of said pockets when the slide is in one extreme position and with the other when the slide is in the opposite extreme position.

13. In a machine of the character described, the combination of a casing, providing two storage receptacles; an interposed coin chute; a slide, extending through the casing from side to side below the storage receptacle, said slide having a raised central portion movable alternately beneath the said storage receptacles; and two independent coin disabled locking means, carried in said raised portion; a coin pocket, for each said lock and positioned in the raised portion of the slide and movable alternately into register with the said coin chute.

14. In a machine of the character described, the combination of a slide, having a central raised platform, for package ejection; two independent coin pockets, carried 100 by said platform portion; and independent coin disabled slide locking means, associated with each of said pockets; a plate, guidingly supporting said slide; and means, on said plate, engaged by said locking means to release the coin.

15. The combination of a coin controlled slide, movable into two extreme positions; a flat support therefor, the central part of said slide being elevated to form a table, with 110 side walls; a member, inserted within the opening formed under the table and having side walls spaced from the side walls of the table to provide two coin receiving pockets; and a coin disabled slide lock, positioned in 115 each of said pockets.

16. In a machine of the character described, the combination of a casing, providing two separate storage compartments; a bridge plate, spanning said casing below 120 said compartments; a slide, transversely movable on said bridge plate, providing a central platform, flanked by delivery recesses, said slide being movable to bring either delivery recess into register with one 125 storage compartment, and the platform into register with the other storage compartment, and the remaining recess into exposed position beyond the wall of the casing; and two independent coin controlled locking means, 130

carried by said central platform, and adapted to register alternately with said coin chute.

17. The combination of a coin controlled slide, a flat plate supporting the same, a vertically positioned, coin disabled dog pivoted on a horizontal axis and positioned within a vertically disposed coin receiving pocket in said slide, said plate having a slot formed 5 therein, elongated in the direction of slide movement, a finger projecting from said dog into the slot, a spring carried by the slide and coacting with said dog to normally force said finger into contact with one side of the 10 slot, the side of the slot in engagement with said finger being cam shaped substantially as and for the purpose set forth.
18. The combination of a coin controlled slide, a flat plate supporting the same, two 15 vertically disposed coin receiving chambers 20

in said slide, a vertically positioned coin disabled dog in each of said chambers, said plate having formed therein a slot elongated in the direction of slide movement, a finger projecting from each of said dogs 25 into the said slot and normally spring pressed into engagement with one side thereof, the side of said slot in engagement with the said finger being cam shaped and provided with a projecting part at its longitudinal center for alternative engagement by the said fingers to hold the dogs in coin receiving position.

In testimony whereof I hereunto set my hand in the presence of two witnesses.

EMERSON A. BOLEN.

In the presence of—

W. LINN ALLEN,
MARY F. ALLEN.
